UNITED STATES PATENT OFFICE.

GEORGE L. ROBINSON, OF BEECHVIEW, PENNSYLVANIA, ASSIGNOR TO BLAW-KNOX COMPANY, OF PITTSBURGH, PENNSYLVANIA, A CORPORATION OF PENNSYLVANIA.

FEED HOPPER FOR GAS PRODUCERS.

1,425,901.

Specification of Letters Patent. Patented Aug. 15, 1922.

Application filed July 30, 1920. Serial No. 400,272.

To all whom it may concern:

Be it known that I, GEORGE L. ROBINSON, a citizen of the United States, residing at Beechview, Allegheny County, Pennsylvania, have invented a new and useful Improvement in Feed Hoppers for Gas Producers, of which the following is a full, clear, and exact description, reference being had to the accompanying drawing, forming 10 part of this specification, in which—

Figure 1 is a vertical section showing my invention applied to a gas producer, a portion of the gas producer being also shown in vertical section.

15 Figure 2 is a section on the line II—II of Figure 1, and

Figure 3 is a section on the line III—III of Figure 2.

My invention has relation to feed hoppers for gas producers, and is designed to provide efficient means for cooling those portions of the hopper which are most affected by the heat to which they are subjected in use. In hoppers of this class, considerable 25 difficulty has been experienced in maintaining a proper seating of the bell which forms the valve controlling the discharge from the body of the hopper into the producer, owing to the fact that the bell and its seat become 30 warped by the action of the heat. My invention provides water-cooled means of simple character for overcoming this trouble, and greatly extends the life of the hopper and bell.

35 Referring to the accompanying drawing in which I have shown a preferred embodiment of my invention, the numeral 2 designates a portion of the top of a gas producer having a feed opening 3 surrounded by the 40 usual water pan 4. 5 designates the cylindrical body of my improved feed hopper which is preferably formed from sheet metal, its upper edge being flanged outwardly, as shown at 6, to seat the cover 7; and its lower portion being contracted inwardly, as shown at 8, to form the hopper proper below the throat of which the metal 45 is again bent outwardly, as shown at 9, to form a seat for the upwardly seating bell 10. The lower edge portion of the metal 50 forming the body of the hopper is flanged outwardly, as shown at 11, to seat upon the flange 12 surrounding the opening 3 in the producer top.

55 13 is the outer wall of a water container

14 whose inner and bottom walls are formed by the lower portion of the hopper body. This wall is suitably secured, as by welding, to the base flange 11 of the hopper. The top of the container 14 is closed in any suitable 60 manner as by the angles 15. 16 designates a water inlet pipe, and 17 a water discharge pipe for the container, the latter being shown as discharging into the water pan 4. 18 designates the weighted lever for actuating the bell 10 to which its inner arm is connected by the link 19. To form a support for the fulcrum 20 of this lever, a bracket 21 is provided which is bolted or riveted to the body of the hopper, as indicated at 22, this 70 bracket fitting over the opening 23 in the hopper body through which the lever extends.

The entire hopper may be removably secured to the producer by any suitable means, 75 such as removable bolts 24.

It will be noted that the construction and arrangement of the water container 14 is such that a considerable body of water is provided closely adjacent to the seat for the bell 10, thereby effectively preventing such seat and bell from warping. The entire construction is a simple and relatively inexpensive one. I do not wish to limit myself to the particular construction and arrangement which I have shown, since it is obvious that the advantages of my invention can be obtained, notwithstanding considerable variations in the details of construction and without departing from the spirit 80 and scope of the appended claims.

I claim:

1. A gas producer having a top, a feed hopper removably secured to the top and having a seat for a valve or bell, and means 95 for water-cooling the seat, substantially as described.

2. A gas producer having a top with a hole therethrough for the introduction of fuel and having an upstanding flange 100 around the hole, a feed hopper removably secured to the top of said flange and having a seat for a valve or bell, and means for water-cooling the seat, substantially as described.

3. A feed hopper for gas producers, comprising a hopper body formed of sheet metal, said body having its lower portion shaped to form the hopper proper and to form upwardly and inwardly sloping valve 110

seat below the throat of the hopper, and a liquid containing chamber surrounding the throat and seating portions of the hopper, and having its inner wall formed by such portions, together with means for circulating a cooling liquid through said chamber, substantially as described.

4. A gas producer having a top formed with a pan for cooling water and having a

hole therethrough for the introduction of fuel, an upstanding flange surrounding the hole, a feed hopper removably secured to the top of said flange, and having a seat for a valve or bell, and means for water-cooling the seat, substantially as described.

In testimony whereof, I have hereunto set my hand.

GEORGE L. ROBINSON.
